UNITED STATES PATENT OFFICE.

JOHN H. WOOLLISCOFT, OF GREAT CROSBY, NEAR LIVERPOOL, ENGLAND.

LIQUID ELECTRIC RESISTANCE.

1,360,069.

Specification of Letters Patent. Patented Nov. 23, 1920.

Application filed April 17, 1916. Serial No. 91,693.

To all whom it may concern:

Be it known that I, JOHN HAROLD WOOLLISCOFT, a subject of the King of Great Britain, residing at Great Crosby, near Liverpool, in the county of Lancaster, in the Kingdom of England, have invented certain new and useful Improvements in Liquid Electric Resistance, of which the following is a specification.

10 The present invention relates to improvements in arrangements for altering the resistance in an electric circuit of the type in which a conducting medium flows by gravity from one chamber to another at a predetermined rate.

According to the present invention a liquid resistance is provided where electrolyte can pass by percolation from one chamber to another to alter resistance in an electric circuit in an effective and efficient manner. The chambers are interconnected in such manner that air or gas can move from one chamber to the other to allow a free percolation of the electrolyte in the reverse 25 direction.

Further the chambers have communications with the outside or atmosphere such that as liquid passes from one chamber to the other the entering liquid displaces gases 30 of electrolysis from that chamber to the outside, while the liquid leaving the other chamber induces air in equal volume from the outside.

In the arrangement of the present invention the medium, usually liquid, may flow gradually into the chamber containing electrodes in known manner but is arranged to be able to flow rapidly from the said electrode chamber so that the circuit is slowly 35 made and rapidly broken.

The present invention is more particularly described with reference to the accompanying drawings, in which:—

Figure 1 is an outside elevation of one 45 form of the device, while

Fig. 2 is a part sectional view corresponding thereto.

Fig. 3 is an outside elevation of a modification.

Fig. 4 is a view corresponding to Fig. 3, showing the parts in a different position.

Fig. 5 is a view of a valve being a detail of the device shown in Figs. 3 and 4.

The drum 1 is formed of two semi-cylindrical parts united together and mounted on trunnions 2. The casing is provided with an

operating handle 3 whereby it may be moved about the trunnions 2.

The drum 1 is divided into two portions 7 and 8 shown equal but if desired, can also be unequal, by a diaphragm 4. An electrode 5 is mounted in one chamber 7, insulated from the casing 1, which may form the other electrode. The casing is weighted as at 6 so that it normally lies in such a position that the electrode 5 is completely out of connection with the conducting liquid, such as the solution of an electrolyte which will lie in the chamber 8, to partly fill the same.

The diaphragm 4 is provided with a hole 70 or holes 10^a shown very enlarged so that liquid may percolate through from one chamber 8 into the other chamber 7 of the casing 1. The diaphragm is provided with a plate valve 9 pivoted at a point 10' and if desired provided with a plate 10 or counter-weighted, to insure the trapping of the liquid in the chamber 8. The hole or holes above mentioned to allow the liquid to pass from one chamber 8 to the other 7 may be arranged 80 at the abutting faces of the plate valve 9 with the diaphragm 4.

In operation of the device the casing is turned about the pivot 2 by means of the handle 3. The electrolyte then previously 85 lying in the circular bottom of the chamber 8, will bear on the valve 9, the weight of the water serving to hold this closed. The electrolyte will then percolate through the hole or holes provided, into the chamber 7 90 and commence to cover the electrode 5 to an increasing degree, reducing the resistance between electrode 5 and the casing 1.

When it is desired to replace the full resistance in circuit, or in fact open circuit, the 95 handle 3 is returned to the position shown in Fig. 1. Owing to the fact that the pivotal point 10' of the valve 9 is not arranged midway along the valve, but at one side, two openings are simultaneously provided, the 100 electrolyte or liquid being adapted to pass through the maximum opening to the empty chamber 8 at the lower portion, with practically no restriction or disturbance, while the air displaced passes into the other chamber 105 through the top-portion of the valve.

The rising liquid in the chamber 8 acts as a piston driving out the gases of electrolysis through the vent hole 50. The liquid will draw in fresh air automatically 110 as required through the port 37.

A no-voltage coil or controlling magnet

11 is arranged on the frame 12 supporting the casing 1 and is provided with an armature having a hook catch 13 adapted to engage a catch 14 on the casing 1. When the 5 casing is turned by means of the handle from the position shown in full lines in Figs. 1 and 2 to the position shown in dotted lines in Fig. 2, the catch 14 will engage with the hook 13 and the hook will hold the casing 10 in this position against the tendency of the counter-weight 6 to return it to the normal full line position.

In Fig. 1 of the drawings, the motor is indicated at M, the two main lines furnishing current to the motor are indicated at *a* and *b*. The line *a* is connected to one of the brushes of the motor. The line *b* is connected to the pivot 2 of the case and thus through this pivot to the casing. The 20 line *c* leading to the other brush in the motor is a part of the main line *b* and this line *c* is connected to the arm 15. The arm 15 is adapted to make contact with a segment 36 which is insulated from the casing 25 and connected to the insulating pin 55 supporting and in circuit with the electrode 5. Thus it will be seen that the resistance above described is thrown into the line *b* leading to the motor. The post 18 is separate from 30 the segment 36 and is directly connected to the casing so that, if the arm 15 makes contact with the post 18, then the resistance will be cut out and current through the line *b* will pass to the pivot 2 and thus to the 35 casing and through the casing to the post 18 and from the post 18 through the line *c* to the brush of the motor.

The electro-magnet 11 is provided with the usual coil and one terminal of this coil 40 is connected through a line *d* to a resistance *R* which may be the field resistance of the motor and thus to one of the brushes of the motor. The other terminal of the coil of the electro-magnet 11 is connected to a terminal *e* and through this terminal to a line *f* which is connected to the insulated terminal 38 and also to a terminal *g* of an electro-magnet 17. The other terminal *h* of this electro-magnet 17 is connected by the 45 line *i* with the main line *b*. The switch *S* is a short circuit switch used for cutting out the electro-magnet 11. When the casing is in the dotted line position and held by the locking catch 13, the armature carrying this locking catch will hold the catch in locking position so long as the coil of the 50 electro-magnet is energized. If the circuit is broken, then this catch will release the armature and will release the latch 13 and 55 this will release the casing, so that it will swing again to the full line position.

It will be noted that the contact 38 is normally covered by the electrolyte in the casing and this establishes a circuit between 60 this terminal and the casing. When the cas-

ing is turned to the dotted line position, the electrolyte begins to slowly run through the opening or openings 10^a to the side 7 of the casing, gradually reducing the resistance as the motor gets under way. As soon as the electrolyte uncovers the terminal 38, then the current is broken between the terminal 38 and the casing with the following result:—The electro-magnet 17 is shunted across, the main lines being connected, on 70 the one hand, with the line *b* and on the other hand, through the resistance *R* with the line *a*. Except for the connections through the terminal 38, current would be supplied to this electro-magnet as soon as 75 current is turned on the lines, but the terminal 38 serves to short circuit the connection through the electro-magnet 17, therefore when the current is first turned on the electro-magnet 17 is not influenced. The shunt 80 circuit for the electro-magnet 17 is short circuited through the contact 38 and the electrolyte and casing. Just as soon, therefore, as all the resistance is thrown out of the main line, then the terminal 38 is uncovered, the electro-magnet is energized, and operating upon the armature 16, will swing the arm 15 from the dotted line position, shown in Fig. 1, to the full line position 85 shown therein, and when the casing is in the dotted line position, then this arm 15 will contact with the post 18 and this cuts out the resistance. It will thus be apparent that the resistance can be thrown in for starting and after it has been gradually reduced to a minimum amount, it will be automatically cut out. The casing, however, 90 will remain in the dotted line position during the operation of the motor.

Should the current decrease below a pre-determined value the armature of the no-voltage coil 11 releases the catch 13 so that the casing 1 will automatically turn back by reason of the counter-weight 6 into the initial position shown in full lines in Fig. 110 2, so that open circuit is again obtained or in certain construction the whole resistance can be again placed in circuit. When the liquid has completely passed through one electrode chamber 7 to the other chamber 8, the 115 valve 9 will close so that it can then only return to the chamber 7 through the leakage holes in the diaphragm 4 or by leakage through the faces of the plate valve 9.

An opening closed by a plug 19 is arranged in the base of the casing 1 whereby the apparatus may be filled or emptied of its conducting liquid or electrolyte.

In the modified construction of Figs. 3 and 4 an arrangement is shown whereby the 125 short-circuiting movement is operated mechanically by the movement of the liquid in the chamber. In this case the valve 9 as shown diagrammatically in Fig. 5, is provided with a counter-weight 20 and catch 130

21 adapted to move against an arm 22 of a bell crank lever mounted in the side of the casing 1 when there is no longer any weight of liquid on its upper face tending to hold 5 the valve 9 in the closed position. Consequently when the liquid has leaked through to the electrode chamber the counter-weight 20 will cause the valve 9 to swing about its pivots and move the arm 22 of the bell crank 10 lever so that its other arm 23 moves against a spring controlled catch 25 which has been engaging a catch 26 arranged on the arm 27 of the bell crank contact lever, the arm 15 of which operates similarly as in the 15 construction described above. That is to say, passing from the position shown in Fig. 3 a loose finger 28 mounted on the side of the casing and operating between stops 29, as the handle 3 is turned over moves 20 against a pin on the arm 27 and turns this down into the position illustrated in Fig. 4 so that the catch 26 engages with the spring catch 25 and this contact arm is therefore held in the position illustrated 25 in Fig. 4. It is held here until there is no further resistance on the valve 9 when the counter-weight 20 operates to release the catch 25, whereby the arm 27 under spring control will move over on to the contact 18 to short-circuit the resistance.

The holes allowing for passage or leakage of the electrolyte from one chamber to the other can be if desired regulated from an outside source so that the rate at which resistance is cut out of circuit may be made as slow or as rapid as may be desired depending upon the work required of the device.

It will be seen that a great advantage of this arrangement is that it is impossible to 40 cut out resistance too fast when starting up the motor while when the motor is cut out, the circuit across the electrode is very rapidly broken thus rendering the switch substantially fool-proof and easily manipulated.

It will be understood that while this device has been described with relation to an ordinary starter it might easily be adapted for a regulator for reversing electric 50 motors.

I declare that what I claim is:—

1. An electric liquid resistance comprising a pair of chambers, electrodes in said chambers, a mass of liquid, means to provide 55 rapid passage of said liquid by gravity in one direction, and means to control percolation by gravity at a predetermined slow rate of the liquid in the reverse direction.

2. An electric liquid resistance comprising 60 a chamber, electrodes, a partition dividing said chamber into two parts, a one-way valve in said partition, electrodes, and means to transfer air and gas from one side to the other as liquid passes by gravity in the reverse direction.

3. An electric liquid resistance comprising a chamber, electrodes, a partition dividing said chamber into two parts, a one-way valve in said partition, means to transfer air and gas from one side to the other as liquid 70 passes by gravity in the reverse direction.

4. An electric liquid resistance comprising a chamber, electrodes, a partition dividing said chamber into two parts, a two-passage one-way valve in said partition, air or gas 75 inlet and exhaust means to said chamber, and a mass of liquid electrolyte passing from one chamber to the other by gravity.

5. An electric liquid resistance comprising two chambers, electrodes, means connecting 80 said chambers to allow flow of liquid from one chamber to another by gravity at a pre-determined slow rate, and means connecting each chamber with the atmosphere.

6. An electric liquid resistance comprising two electrodes, a mass of liquid operating as an electrolyte, and a valve connecting said chambers to allow rapid passage of liquid by gravity in one direction and slow percolation 85 by gravity in the other direction. 90

7. An electric liquid resistance comprising two chambers, electrodes, a mass of liquid, a plate valve connecting said chambers, pivots carrying said plate valve, and means to allow said plate valve to open in one 95 direction only while allowing slow percolation of the liquid by gravity when said valve is closed.

8. An electric liquid resistance comprising two chambers, electrodes, a mass of liquid, 100 a plate valve connecting said chambers, pivots carrying said plate valve unsymmetrically situated with regard to it so that liquid may pass through the large half in one direction as gas passes through the small 105 half in the other direction, and means to constrain said plate valve to open in one direction only while allowing slow percolation of the liquid by gravity when the valve is closed. 110

9. An electric liquid resistance comprising two chambers, electrodes, a mass of liquid, a diaphragm separating said two chambers, a plate valve in said diaphragm extending from the periphery of said chambers to beyond the center, pivots supporting said plate valve substantially at the center of the diaphragm and unsymmetrically of the plate valve, and means to constrain said plate valve to open in one direction only while 115 allowing slow percolation of liquid by gravity when said valve is closed. 120

10. An electric liquid resistance comprising a drum, a partition dividing said drum into two parts, electrodes in one part, a mass 125 of liquid electrolyte, trunnions supporting said drum centrally, means to turn said drum on said trunnions, means to allow percolation by gravity of said liquid through said partition, means to control the entry 130

or exhaust of air and gas to the two parts of said drum, a counterweight for holding said drum in a predetermined position, and a catch for holding the drum in the position 5 with the part having the electrodes uppermost.

11. An electric liquid resistance comprising a drum, a partition dividing said drum into two parts, electrodes in one part, a 10 mass of liquid electrolyte, trunnions supporting said drum centrally, means to turn said drum on said trunnions, means to allow percolation by gravity of said liquid through said partition, means to control 15 the entry or exhaust of air and gas to the two parts of said drum, a catch for holding the drum in the position with the part having the electrodes uppermost, and means to return said drum automatically to the position 20 in which the part with the electrodes is beneath.

12. An electric liquid resistance comprising a drum, a partition dividing said drum into two parts, electrodes in one part, a mass 25 of liquid electrolyte, trunnions supporting said drum centrally, means to turn said drum on said trunnions, means to allow percolation by gravity of said liquid through said partition, means to control the entry or

exhaust of air and gas to the two parts of 30 said drum, and means to rapidly transfer electrolyte from one part to the other in the opposite direction to said percolation.

13. An electric liquid resistance comprising 35 a drum, a partition dividing said drum into two parts, electrodes in one part, a mass of liquid electrolyte, trunnions supporting said drum centrally, means to turn said drum on said trunnions, means to allow percolation by gravity of said liquid through 40 said partition, means to control the entry or exhaust of air and gas to the two parts of said drum, a counterweight for holding said drum in a predetermined position, a catch for holding the drum in the position with 45 the part having the electrodes uppermost, and means to rapidly transfer electrolyte from one part to the other in the opposite direction to said percolation.

In witness whereof, I have hereunto 50 signed my name this 23rd day of March 1916, in the presence of two subscribing witnesses.

JOHN H. WOOLLISCROFT.
